Borsig Berlin-Tegel, Berlin-Tegel, Germany, a
corporation of Germany

Application February 26, 1938, Serial No. 192,705
In Germany April 19, 1937

9 Claims. (Cl. 62—114)

This invention relates to means for cooling liquids, and refers more particularly to an apparatus for extracting paraffin from mineral oils.

In prior art, the extraction of paraffin from mineral oils is often carried out by circulating the oil through a horizontally disposed cooling pipe or chiller, a cooling medium, such as liquid ammonia, flowing along the outer surfaces of this pipe. Paraffin is crystallized by this cooling and deposited upon the inner surfaces of the pipe. Then the paraffin is scraped off the walls of the pipe by special scraping devices, which may have the form of spiral bodies, and is carried through the chiller by the oil, which is later sent through a filter wherein paraffin crystals are separated from the oil.

The disadvantage of this construction is that it requires the use of expensive and exactly fitting scrapers in the chiller. The manufacture of the chillers is a comparatively difficult and expensive task, since the inner diameters of ordinary pipes may vary to a great extent; for example, a pipe of an average diameter of 150 mm. may have variations in diameter amounting to as much as 3 mm. Therefore, in order to provide a perfect fit for the scraping devices, it is necessary to use bored-out pipes, thus increasing the manufacturing costs to a considerable extent. If, in order to avoid such high expense, pipes of the usual type are used, paraffin is permanently deposited upon the walls of the pipes, thereby lowering greatly the amount of the transmitted heat.

An object of the present invention is to eliminate these drawbacks by providing a device for extracting paraffin which is comparatively inexpensive to manufacture and which operates with an excellent coefficient of heat transmission.

Other objects of the present invention will be apparent in the course of the following specification.

The objects of the present invention may be realized by causing the cooling medium to flow downwardly in the form of a thin layer along the inner wall of a rotating vertical cooling cylinder which is surrounded by oil. It is advantageous to combine several vertical cooling cylinders into one group which is provided with one scraping device, such as a scraping roller. Paraffin contained in the oil is then deposited upon the outer surface of the cooling cylinder and is easily removed therefrom, so that it cannot form a permanent layer of crystals which would diminish the coefficient of heat transmission.

It is advisable to provide a continuous circu-

lation of the cooling medium, even though an easily evaporating medium is used, which is supplied in excessive quantities. In order to increase the cooling, the oil from which paraffin has been extracted may be conducted in countercurrent to the cooling medium flowing along the inner wall of the cylinder, the oil being introduced at the lower end of the container enclosing the cooling cylinder and being removed from the upper end of the container.

It may be advantageous to provide an additional container below the container for the oil, this second container being used for receiving the liquid cooling medium and for replenishing it. The container for the cooling medium is provided with vertical channels, preferably extending through the axis of rotation of the cooling cylinder, for conducting the cooling medium to the upper end of the cooling cylinder.

The invention will appear more clearly from the following detailed description when taken in connection with the accompanying drawings, showing by way of example preferred embodiments of the inventive idea.

In the drawings:

Figure 1 is a vertical section through a cooler constructed in accordance with the principles of the present invention;

Figure 2 is a horizontal section along the line 2—2 of Figure 1;

Figure 3 is a horizontal section along the line 3—3 of Figure 1;

Figures 4 and 5 show in horizontal cross-section coolers designed for a greater output;

Figure 6 shows another cooling device in vertical section;

Figure 7 is a horizontal section along the line 1—7 of Figure 6; and

Figure 8 is a horizontal section along the line 8—8 of Figure 6.

The cooling device shown in Figures 1, 2, and 3 of the drawings comprises a cylindrical container 10 which contains three rotary cooling cylinders 20. A motor 13 is situated upon a support 14, which is carried by the cover 12 of the container 10.

The shaft 15 of the motor 13 is firmly connected with a vertical shaft 16 to which an elongated scraping roller or brush 17 is connected. As shown in Figure 1, the vertical cylindrical brush or scraper 17 extends substantially from the top to the bottom of the container 10.

A portion of the shaft 16 is square in cross-section and carries a pinion 18, which is rotatable along with the shaft. The pinion 18 is in

engagement with three toothed wheels 19, which are firmly mounted upon the cooling cylinders 20, so that the three cylinders are rotated by the pinion 18.

5 The cover 12 of the container 10 carries a pipe 21 through which the cooling medium is introduced. An annular chamber 22 is provided within the cover 12 and is in communication with the pipe 21. The chamber 22 is also in communication with an opening 25 of a feed pipe 24, which is suspended from the cover 12 and which extends through the chamber 22. As shown in Figure 1, the pipe 24 projects into one of the cylinders 20 and extends through its gear wheel 19.

10 15 Two other pipes similar to pipe 24, which are not shown in the drawings, extend into the interiors of the other two cylinders 20. Since the devices pertaining to each of the three cylinders 20 are the same in construction and operation, 20 only one of them will be described in this specification.

Another annular chamber 26 is situated above the chamber 22 and is used for collecting the vapors of the cooling medium. A second pipe 27 is suspended from the cover 12 adjacent the pipe 23. The pipe 27 also extends through a gear wheel 19 and into the interior of a cylinder 20, and is provided with an opening 28 communicating with the chamber 26. The chamber 26 is also 30 in communication with a pipe 29 carried by the cover 12 and used for the removal of the gaseous cooling medium.

Another inner chamber 30 is provided within the cover 12 and is enclosed by the walls 31. A 35 plate or cover 32, which carries the support 14 for the motor 13, constitutes a cover for the chamber 30 and carries a pipe 33 through which crude oil may be introduced into the chamber 30. The bottom plate 34 of this chamber is provided 40 with several openings 35 through which the oil may flow into the interior of the container 10 and upon the rotating cylinders 20.

The bottom plate 11 of the container 10 is hollow and comprises an annular chamber 49 having inner walls 48. A plate 36 constitutes the cover for the chamber 49 and carries a vertical pipe 37 by means of which the cooling medium can be introduced into the chamber 49. A pipe 38 carried by the plate 11 is used for the removal 50 of the cooling medium.

Conical walls 39 are disposed in the middle of the bottom plate 11 and form a trough used for the removal of the scraped-off paraffin and the oil carrying the same.

55 The cooling medium circulating through the cylinders 20 is prevented from mixing with the oil by means of a packing 40 enclosing the pipes 24 and 27 and a packing 41 enclosing the pipe 37. In the device shown in Figure 1, these packings 60 have the form of concentric cylinders which are partly filled with mercury, although, obviously, stuffing boxes or other suitable devices may be used for the same purpose.

65 Each of the cylinders 20 carries a plate 42 which encloses the pipe 27 and is suspended from the top of the cylinder by the supports 43, so that it rotates along with the cylinder.

The operation of the device is as follows:

Crude oil is introduced through the pipe 33 into 70 the chamber 30 and penetrates through the openings 35 formed in the bottom of that chamber into the interior of the container 10. The oil drops upon the gear wheels 19 of the three containers 20 and flows along the outer surfaces of these 75 containers.

However, the oil may also be conducted to the outer walls of the scraping roller 17 and applied by this roller to the outer surfaces of the cylinders 20 in the form of a thin layer.

When the motor 13 is switched on, its rotation 5 will be transmitted through the shaft 15 and the shaft 16 to the pinion 18 and the gear wheels 19 meshing therewith, so that the cylinders 20 will be rotated along with the scraping roller 17. Therefore, the oil which is applied to the outer 10 surfaces of the rotating cylinders 20 will flow down these surfaces in the form of helical windings.

The cooling medium, which may be liquid ammonia, brine, or the like, is introduced through 15 the pipe 21 into the chamber 22 situated within the cover 12. Then the cooling medium flows into the interior of the pipes 24 through their openings 25 and is thus introduced into the cylinders 20; it falls upon the plates 42 and is projected against the inner walls of the cooling cylinders 20 by the centrifugal forces developed in the course of the rotation of the plates 42. The cooling medium subjected to the centrifugal and gravitational forces flows downwardly along the 25 inner walls of the cylinders 20 and will absorb an amount of heat sufficient for at least a partial evaporation of the cooling medium, said heat coming from the oil surrounding the cooling cylinders 20. 30

Due to this cooling of the oil, paraffin is crystallized and deposited upon the outer walls of the cooling cylinders 20 and is immediately scraped off by the scraping roller 17, which rotates with a speed different from that of the cylinders 20. 35 The scraped-off crystallized paraffin particles remain in suspension in the oil and are carried by it, the oil carrying the paraffin particles flowing through the trough 39 to a filtering device, not shown in the drawings, where paraffin is separated from the oil.

The vaporized ammonia rises through the pipe 27 into the chamber 26 and is removed through the pipe 29.

The remaining liquid ammonia is collected at 45 the bottom of the rotary cylinders 20 and flows through the pipe 37 into the chamber 49 of the bottom plate 11, being removed from the device through the pipe 38.

The time required for the flow of the cooling 50 medium can be easily regulated by the proper selection of the speed of rotation of the cooling cylinders 20. The oil can be caused to flow along the outer walls of the cylinders 20, or, as is assumed in the construction shown in Figure 1, 55 the container 10 may be filled with oil. In the latter case, the rotation of the cooling cylinders furthers the exchange of heat, due to a difference in speed between the rotating walls of the cylinders 20, the oil movable therewith and the 60 remaining oil, which fills the container 10.

The constructions shown in Figures 4 and 5 of the drawings are used for plants of comparatively large dimensions. Figure 4 shows a central cylinder 50 which is surrounded by three scraping 65 rollers 51 and five outer rotary cylinders 52, which are all enclosed in a container 53.

In the construction shown in Figure 5, there is an inner ring of six rotary cylinders 60 which is enclosed by six scraping rollers 61 surrounded by 70 twelve outer cylinders 62, the entire aggregate being situated within a container 63.

In each of these devices, the rotary cylinders are arranged in groups of three, each group being in contact with one scraping roller, all of the 75

cylinders being driven from the middle of the container. By these means it is possible to provide large cooling surfaces within a comparatively small area.

5 The device shown in Figures 6 to 8 of the drawings comprises a cylindrical container 70 which encloses three rotary cylinders 71. The outer surfaces of these three cylinders are engaged by a scraping roller or brush 72 which is situated in the middle of the container 70 and which is rotatable along with its shaft 73 driven by a motor 74 which is preferably situated above the container 70. The cover 75 of the container 70 carries the support 76 for the motor 74. A pinion 77 is firmly mounted upon shaft 73 and meshes with three gear wheels 78, each of which is firmly connected with a separate rotary cylinder 71. The container 70 carries a bottom plate 79 which is firmly connected therewith and which 20 supports the rotary cooling cylinders 71.

A second container 80 is situated below the container 70 and is provided with an inner horizontal plate 81 which divides the interior of the container 80 into two chambers 82 and 83. A pipe 84, which is carried by the container 80 and which is in communication with the chamber 82, is used for introducing the liquid cooling medium into the container 80 and may be closed by a valve 85 operated by a float 86.

30 Another pipe 87 which is used for the removal of the gaseous cooling medium is carried by the container 80 and is situated close to the cover 88 of the container.

A long vertical pipe 89 is supported by the partition plate 81; the lower end of this pipe is in communication with the chamber 83 formed in the container 80. The pipe 89 extends through one of the cylinders 71 and its upper end is situated close to the gear wheel 78 carried by that cylinder. The pipe 89 passes through an opening formed in the cover 88, said opening being closed in an airtight manner by means of the stuffing box 90, and through an opening which is formed in the bottom plate 79 and which is closed by the stuffing box 91. A plate or disc 101 is situated at the upper end of the cooling cylinder 71 and is rotatable therewith. The upper end of the pipe 89 extends through the disc 101 and terminates just above that disc.

50 Similar pipes 89 are situated within the other two cylinders 71. Since the construction is the same for all the three cylinders, only one of them will be hereinafter referred to in the specification.

55 Pipes 92 are situated between the containers 70 and 80 and enclose the long pipes 89. The lower ends of the pipes 89 are in communication with the chamber 83 of the container 80 (Fig. 6). The pipes 92 are also in communication with the cylinders 71 and are rotatable therewith.

The two chambers 82 and 83 of the container 80 are in communication with each other by means of a pipe 93 which extends through the chamber 83 and which connects the chamber 82 with a bent pipe 94 carrying a valve 95. The other end of the pipe 94 is connected to a centrifugal pump 96, the opposite side of which is connected by a pipe 97 carrying a valve 98 with the lower chamber 83 of the container 80.

70 The container 70 is provided with a bottom branch pipe 99 and a top branch pipe 100.

The device is operated as follows:

75 Crude oil or any other liquid which is to be cooled in the device is introduced into the in-

terior of the container 70 through the pipe 99 and gradually fills the container.

The cooling medium, for instance ammonia, is introduced into the chamber 82 of the container 80 through the pipe 84 having a valve 85, which 5 regulates the amount of the cooling medium in circulation. The evaporated cooling medium leaves the chamber 82 through the pipe 87, is liquified by a compressor, not shown in the drawings, and is then returned to the chamber 82 10 through the pipe 84.

When the pump 96 is switched on, it will pump the liquid ammonia contained in the chamber 82 through the pipes 93, 94 and 97 into the lower chamber 83 of the container 80 and into the pipes 15 89, causing it to rise within these pipes until it reaches the upper ends thereof. Liquid ammonia flowing out of the upper ends of the pipes 89 will drop upon the plates 101 which are rotatable along with the containers 71. Due to the centrifugal 20 forces, ammonia will be directed toward the inner walls of the containers 71 and will flow by gravity through the openings formed upon the periphery of the discs 101 and down the inner surfaces of the containers 71 in countercurrent to the flow of 25 the crude oil which rises within the container 70 and flows upward along the outer walls of the cylinders 71. A part of the ammonia will be evaporated and paraffin will be deposited upon the outer walls of the rotary cylinders 71. Ammonia 30 remaining in the liquid state will flow down the pipes 92 into the chamber 82 of the container 80. Crystallized paraffin is removed from the side walls of the cylinders 71 by the scraping roller 35 72 and remains in suspension in the oil, which is removed from the container 70 through the upper branch pipe 100 and is poured into a filtering device.

Since the liquid cooling medium is subjected to constant circulation, the device can be advantageously used in connection with plants using a cooling medium which does not evaporate in the course of the cooling process. For example, it is possible to treat the mineral oil in two stages; the first stage consisting of a preliminary cooling 45 by a filtrate having a comparatively low temperature. In the second or next stage an evaporating cooling medium, for instance ammonia, may be used.

Whenever a low temperature filtrate is used for 50 a preliminary cooling of the crude oil, the pump 96 is switched off and the container 80 is used as a heat exchanger. The low temperature filtrate is then caused to flow downwardly along the inner walls of the cooling cylinders instead of the evaporating cooling medium, while the oil may be caused to circulate in the same manner as in the other stages, namely, by being introduced into the container 70 through the pipe 99 and by being removed through the pipe 100.

55 The described devices are considerably cheaper in the manufacture and installation than prior art devices having the same output.

Furthermore, devices constructed in accordance with the present invention may be advantageously employed for carrying out other processes involving an exchange of heat. They are particularly advantageous for certain methods requiring a very rapid heat exchange and the greatest possible transmission of heat. The surfaces used 70 for the exchange of heat are considerably smaller than the surfaces of prior art constructions and the time required for the treatment is considerably shorter, so that a greater output may be attained.

The cost of construction is low, particularly since no special treatment and precision are required for the manufacture and installation of the cooling cylinders and the scraping rollers. A particular advantage of the described constructions is that the continual cleaning of the surfaces of the cooling cylinders is automatic and thorough. Furthermore, the driving means for the scraping rollers and the cooling cylinders are situated within a container through which oil flows continuously, so that thorough lubrication is assured.

It is apparent that the specific illustrations shown above have been given by way of illustration and not by way of limitation, and that the structures above described are subject to wide variations and modifications without departing from the scope of the invention. For example, the described constructions can be used not only for the extraction of paraffin from mineral oils, but also for the cooling of other liquids which cause the deposit of crust-like layers upon a cooling surface. It is immaterial for the purposes of the present invention whether the scraping rollers and the cooling cylinders are interconnected by separate drives or are merely in frictional engagement with each other, or whether the cooling cylinders are used for driving the scraping rollers or vice versa. All of such and other variations and modifications are to be included within the scope of the present invention.

What is claimed is:

1. A device for cooling liquids, comprising a plurality of vertical cooling cylinders constituting a single group, each of said cylinders having inner and outer heat-transmitting surfaces, a single scraping device in contact with the outer surfaces of all of said cylinders, means rotating said cylinders and said scraping device at different speeds to cause said outer surfaces to move relatively to said scraping device while in contact therewith, means causing the flow of a cooling medium along and in contact with said inner surfaces, and means causing the liquid to be cooled to contact said outer surfaces.

2. A device for cooling liquids, comprising at least one cooling cylinder having inner and outer heat-transmitting surfaces, means causing the flow of a cooling medium along and in contact with said inner surface, scraping means in contact with said outer surface, means connected with said cooling cylinder for moving its outer surface relatively to said scraping means while it is in contact therewith, and a container adapted to contain the liquid to be cooled and enclosing said cooling cylinder, the second-mentioned means and the third-mentioned means, whereby the liquid in said container is in contact with said outer surface.

3. A device for cooling liquids, comprising at least one cooling cylinder having inner and outer heat-transmitting surfaces, means constituting a channel having an end portion projecting into the interior of said cylinder for the introduction of a liquid cooling medium thereinto, means connected with said cylinder for rotating the same, a plate situated within said cylinder below said end portion and connected with said cylinder, said plate having peripheral openings formed therein and being rotatable along with said cylinder, whereby the liquid cooling medium is caused to flow along and in contact with the inner surfaces of the cylinder, and means causing the liquid to be cooled to contact the outer surfaces of said cylinder.

4. A device for cooling liquids, comprising at least one cooling cylinder having inner and outer heat-transmitting surfaces, a pipe constituting a channel for the introduction of a liquid cooling medium into said cylinder, said pipe projecting into the interior of said cylinder, means connected with said cylinder for rotating the same, a plate situated within said cylinder and rotatable therewith, said plate being connected with said cylinder and having peripheral openings formed therein to cause a flow of the liquid cooling medium along and in contact with the inner surfaces of the cylinder, another pipe constituting a channel for the removal of a gaseous cooling medium from said cylinder, the second-mentioned pipe projecting into the interior of said cylinder, and having an end portion situated below said plate, and means causing the liquid to be cooled to contact the outer surfaces of said cylinder.

5. A device for cooling liquids, comprising at least one cooling cylinder having inner and outer heat-transmitting surfaces, means introducing a liquid cooling medium into said cooling cylinder at one of the ends thereof and causing it to flow along and in contact with said inner surfaces, means causing the liquid to be cooled to contact the outer surfaces of said cylinder, a pipe situated at the opposite end of said cylinder for removing the liquid cooling medium, a mercury-filled sealing container between said pipe and said cylinder, and means constituting a chamber for the liquid cooling medium and in communication with said pipe.

6. A device for cooling liquids, comprising at least one cooling cylinder having inner and outer heat-transmitting surfaces, a container adapted to contain the liquid to be cooled and enclosing said cooling cylinder, whereby the liquid in said container is in contact with said outer surface, another container for the cooling medium, the second-mentioned container being situated below the first-mentioned container, means connected with the second-mentioned container and projecting into the interior of said cooling cylinder for introducing said cooling medium into said container at one of the ends thereof, and means connected with the second-mentioned container and the opposite end of said cooling cylinder for the return flow of said cooling medium from said cooling cylinder into the second-mentioned container.

7. A device for cooling liquids, comprising a plurality of vertical cooling cylinders, each of said cylinders having inner and outer heat-transmitting surfaces, a container adapted to contain the liquid to be cooled and enclosing said cooling cylinders, whereby the liquid in said container is in contact with the outer surfaces of said cylinders, another container for the cooling medium, the second-mentioned container being situated below the first-mentioned container, pipes communicating with the second-mentioned container and projecting into the interior of said cooling cylinders, said pipes having ends situated adjacent the upper ends of said cylinders, whereby said cooling medium is introduced into said cylinders at the upper ends thereof and is caused to flow downwardly through said cylinders, and pipes connected with the upper portion of the second-mentioned container and the lower ends of said cylinder for the return flow of said cooling medium from said cooling cylinders into the second-mentioned container.

8. A device for cooling liquids, comprising at

least one cooling cylinder having inner and outer heat-transmitting surfaces, a container adapted to contain the liquid to be cooled and enclosing said cooling cylinder, whereby the liquid in said container is in contact with said outer surface, another container for the cooling medium, the second-mentioned container being situated below the first-mentioned container, means connected with the second-mentioned container and projecting into the interior of said cooling cylinder for introducing said cooling medium into said container at one of the ends thereof, and means connected with the second-mentioned container and the opposite end of said cooling cylinder for the return flow of said cooling medium from said cooling cylinder into the second-mentioned container, a branch pipe carried by the second-mentioned container and constituting a passage for the introduction of the liquid cooling medium into the second-mentioned container, a valve situated within the second-mentioned container for closing and opening said passage, and a float situated within the second-mentioned container and connected with said valve for operating the same.

9. A device for cooling liquids, comprising at least one cooling cylinder having inner and outer heat-transmitting surfaces, a container adapted to contain the liquid to be cooled and enclosing said cooling cylinder, whereby the liquid in said container is in contact with said outer surface, another container for the cooling medium, the second-mentioned container being situated below the first-mentioned container, a partition wall within the second-mentioned container, said partition wall dividing the interior of said container into an upper chamber and a lower chamber, means connected with said upper chamber and projecting into the interior of said cooling cylinder for introducing said cooling medium into said container at one of the ends thereof, means connected with said lower chamber and the opposite end of said cooling cylinder for the return flow of said cooling medium from said cooling cylinder into said lower chamber, and pumping means connecting said upper chamber with said lower chamber.

HEINRICH SÜSS.
